UNITED STATES PATENT OFFICE.

THOMAS SHIPLEY, OF YORK, PENNSYLVANIA, ASSIGNOR, BY MESNE ASSIGNMENTS, TO YORK ICE MACHINERY CORPORATION, OF YORK, PENNSYLVANIA, A CORPORATION OF DELAWARE.

EVAPORATOR AND BRINE COOLER.

Application filed January 21, 1927. Serial No. 162,573.

This invention relates to refrigeration, and particularly to evaporators intended to be operated in a flooded condition.

An important feature of the invention is the application of forced circulation to the liquid refrigerant in such evaporators. Another feature of the invention is the application of the forced circulation idea to a special type of evaporator installation, in which the evaporator is installed in a confining duct through which brine to be chilled is circulated at a high velocity rate.

The advantages of flooded operation are well understood, but difficulty has always been encountered in maintaining the coils completely flooded, or even approximately so. This arises particularly from the fact that the disengagement of the ammonia vapor does not take place as freely as is desired, and there is a tendency for the vapor to sweep liquid refrigerant out with it and thus cause substantial portions of the evaporator to become gas bound. Much has been accomplished by improvements in the design of evaporators, but those forms which are most favorable to rapid disengagement of the gaseous refrigerant are expensive to construct and often they fail to meet all the requirements of the service. One difficulty is that as the transfer of heat is increased, the tendency of the evaporator to become gas bound is greatly increased, with the consequent reduction of the effective area of the evaporator.

The high velocity circulation brine coolers above referred to, in which the brine velocity in contact with the coils is of the order of 160 feet per minute, form the subject matter of my prior application, Serial No. 106,165, and have demonstrated in practice highly successful operative characteristics, including an unprecedented high heat transfer per square foot of evaporator surface. It is desired, however, to increase still further this heat transfer and efficiency. It has been found that there is a tendency for the evaporator to become gas bound when heavily loaded. This places a definite limit on the capacity of the evaporator.

The present invention involves the use of a suction trap or its equivalent, preferably so related to the evaporator that it will feed liquid refrigerant to the evaporator and maintain the same flooded, in conjunction

with a circulating pump which will draw liquid refrigerant from the trap, force it upwardly through the evaporator, and deliver the liquid refrigerant, together with the vaporized refrigerant derived therefrom, back into the suction trap.

The invention further contemplates a by-pass connection, by means of which the circulating pump may be cut out of the circulating system altogether, allowing this to operate by gravity. When the pump is in operation the by-pass may be used to vary the effective circulation through the evaporator.

Two practical embodiments of the invention are illustrated in the accompanying drawings.

Fig. 1 is a top plan view of a brine tank, showing cans in place and illustrating the location of the circulators, the head box and high velocity duct relatively to the tank.

Fig. 2 is a view partly in elevation and partly in longitudinal axial section through the tank.

Fig. 3 is a fragmentary section on the line 3—3 of Fig. 2, looking in the direction of the arrows, and drawn on a slightly enlarged scale.

Fig. 4 is a section on the line 4—4 of Fig. 2, looking in the direction of the arrows.

Fig. 5 is a diagrammatic representation of a modified form of the invention, in which the invention is applied to cold storage room coils.

In Figs. 1 and 2 the central portion is broken away to indicate that the brine tank may be, and ordinarily is, longer relatively to its width than is shown in these figures.

The brine tank is indicated generally by the numeral 11. It is rectangular in form and is preferably of greater length than width. The depth of the tank is preferably such as to leave only a small interval between the bottoms of the ice cans 12 and the bottom 13 of the tank. While other arrangements are feasible, I prefer and illustrate an arrangement in which the high velocity duct, within which the evaporator is mounted, extends longitudinally through the middle of the tank, dividing the tank into two relatively long and narrow can receiving units. This arrangement has two advantages. First, that it permits an even distribution of the brine flow through each can

receiving portion of the tank, and, second, the interval between the duct and the side of the tank is not too great to be spanned by the frame of a multiple can unit of 5 ordinary size. The duct thus becomes a part of the can supporting structure and the interior of the tank is left clear of can supporting frame work.

The duct is best shown in Fig. 3. It consists of side plates 14 which are flanged and riveted to the bottom 13 of the tank. The side plates 14 are connected by channels 15 which form the top and bottom of the duct. These channels are slightly inclined as 15 shown. At the discharge end (the right hand end as viewed in Fig. 2) the duct terminates at 16 short of the end of the tank, so that brine discharging from this end of the duct, has an opportunity to discharge 20 laterally in opposite directions into the two can receiving portions of the tank. The upper edges of the plates 14 are reinforced by angles 17 and these extend from the head box to the right end of the tank, serving 25 not only to brace the duct structure to the end wall of the tank, but also to support the ends of the frames of the can units.

The head box is at the opposite end of the tank, i. e., the left hand end in Fig. 2. The 30 duct is tightly connected with the head box to which brine is pumped from the head end of the tank, and from which such brine flows to the head or inlet end of the duct. This head box, as is indicated in Fig. 4, is of 35 inverted T-shape. The central portion, indicated generally by the numeral 18, extends the full height of the tank 11 and is closed at the top by a plate 19. This is necessary as considerable pressure head is developed in the head box by the brine circulators. 40

Projecting laterally from the central chamber 18 of the head box are lateral extensions 20, whose depth is less than the 45 depth of the tank. The central chamber 18 and the extensions 20 are formed of plates 21, 22 and 23, riveted to each other and to the walls of the tank. The top plate 22 of each extension 20 is formed with an aperture 50 in which is mounted the housing 24 of a brine circulator of any suitable type. In the drawing there is chosen for illustration a known type of brine circulator which makes use of a screw propeller 25 driven through 55 a shaft 26 by any suitable means, such, for example, as an electric motor. The frame 27 which is carried by the tank structure 11, supports and positions such driving means. As will be readily understood, the plates 14 60 and channels 15 are tightly connected to the plate 23, which plate is formed with an aperture registering with the entrance end of the duct.

The brine drawn from the head end of the 65 tank by the circulators, passes by way of

extensions 20 and central chamber 18, to the duct, flows through this duct to the opposite end thereof and there discharges. The discharging brine divides into two streams, one of which returns through one 70 side section of the tank and the other through the other side section. The cans are mounted in the tank so as to leave a substantial interval 28 between the last can unit and the end of the tank, through which 75 interval the brine discharging from the duct flows laterally, thus insuring a relatively even distribution of the flow between the cans toward the head box.

The mounting of the cans is shown in 80 Figs. 1 and 4. Each can unit comprises five cans 12, supported by a bar frame 29. Each can unit is filled and dumped as a group. The bar frames 29 extend beyond the ends 85 of each group, one end being supported on the angle 17 and the other on an angle 30 riveted to the wall of the tanks (see Figs. 3 and 4). Any preferred mode of supporting the cans, either singly or in groups, might be adopted, but that shown is preferred because the removal of all the can 90 units exposes the entire tank structure.

The evaporator consists of two identical units each comprising a vertical top or off-take header 35, a horizontal bottom or supply header 36, and a plurality of tubes 37 connecting said headers. Each tube extends first vertically upward from the header 36 and is bent so that it extends through the duct at an inclination conforming to the inclination of the duct. The purpose of inclining the duct and the tubes, is to insure a relatively free disengagement of vapor in the event that gravity circulation instead of forced circulation is availed of. 100 This practice is intended to be followed during the periods of light load. 105

The supply headers 36 are fed through a liquid refrigerant line 38 and manifold 39, while the headers 35 discharge through a manifold 40 and off-take pipe 41, larger than the pipe 38, into the suction trap 42. Here liquid and gaseous refrigerant separate and the gaseous refrigerant passes off through the suction line 43. The liquid refrigerant is fed to the trap 42 from the receiver 44 by way of dip pipe 45, and a float valve, consisting of a float chamber 46, float 47 and float controlled valve 48. The pipe 45 discharges liquid refrigerant through the 110 valve 48 into chamber 46, and chamber 46 is in free communication with trap 42 by way of pipe 49. There is a pressure equalizing connection 50 between the float chamber 46 and the suction trap 42 above the 115 liquid level therein. 120

The float 47 is preferably so adjusted as to maintain the liquid level in the trap 42 slightly below the discharge end of the pipe 41. 130

The structure so far defined conforms generally to one embodiment of the invention illustrated and claimed in my prior application above identified.

5 As in said prior application, there is a liquid line connection 51 which leads from the bottom of the trap 42 to the pipe 38. This connection is supplied with a stop valve 52. A circulating pump 53 driven 10 by a motor 54 is interposed in a by-pass around the valve 52. This by-pass consists of an inlet pipe connection 55 controlled by a valve 56 and an outlet pipe 57 controlled by a valve 58. If the valves 56 and 58 are 15 closed and the valve 52 is open, the evaporator functions as an ordinary gravity fed flooded evaporator. If the valves 56 and 58 are opened and the pump 53 is operated, there is a forced circulation from the trap 20 42 through the pump 53 to the bottom headers 36 and thence through the tubes 37 to the top headers 35. From the top headers 35 the flow continues through the pipe 41 back to the trap 42. The rate of forced circulation 25 may be varied by changing the speed of operation of the pump 53, or a simpler regulation may be had by adjusting the valve 52. When this valve is closed a full circulatory flow is had. If the valve be 30 opened more or less the circulatory flow is diminished because the valve 52 offers a circulating by-pass between the suction and discharge of the pump.

The utility of forced circulation of the 35 refrigerant is not confined to the brine cooler field. In Fig. 5 the application of the invention to coolers for use in cooling or hardening rooms is illustrated.

In this figure 61 represents the suction 40 trap, 62 the suction line to the compressor, 63 is a float chamber, 64 a liquid supply line and 65 a valve controlling the supply of liquid refrigerant through the pipe 64 to the chamber 63, the valve 65 being controlled by 45 a float 66. The chamber 63 has top and bottom connections 67 and 68 with the suction trap 61. The evaporator is made up of an upper off-take header 69, a lower or supply header 70, and a plurality of sinuous 50 coils 71, of any suitable form. It is desirable that the coils be so formed as to avoid pockets in which gaseous refrigerant might be trapped.

The liquid refrigerant supply line from 55 trap 61 is shown at 72 and leads through a valve 73 to the suction side of a circulating pump 74. This discharges back through a pipe 75 and valve 76 to the supply header 70 of the evaporator. A by-pass connection 60 controlled by valve 77 is interposed between the pipes 72 and 75 above the valves 73 and 76. If the valves 73 and 76 are closed and the valve 77 opened, the coils 71 may be operated partially flooded, but the preferred operation is to employ forced circu-

lation of the refrigerant. When the pump 74 is running the valves 73 and 76 are of course open. The valve 77 may be opened more or less to reduce the circulatory rate through the evaporator. The valve 77 then 70 acts as a by-pass between the pipes 75 and 72.

The structure shown in Figures 1 to 4 inclusive, involves not only forced circulation of the refrigerant, but the conjoint use of 75 forced circulation of the refrigerant and brine in counterflow relation.

Where the counterflow arrangement is adopted, the warmest brine first contacts with the discharge end of the evaporator, 80 and the most violent evaporation of the volatile refrigerant occurs closely adjacent the vapor offtake. This reduces the flow path for the greater portion of the vapor generated in the evaporator. Thus the advantage 85 is distinctly different from that secured by counterflow where a simple heat interchange between two liquids at different temperatures is sought. Remembering that in the present invention the refrigerant is circulated in a 90 quantity in excess of that which can be evaporated in a single pass through the evaporator, the evaporation would occur with the same heat absorbing effect at any 95 point in the evaporator. The desirability 95 of the counterflow arrangement arises not from the familiar counterflow heat exchange principle, but because of the greater freedom which is afforded for the discharge of the vapor.

An advantage of the invention in both 100 forms of the device illustrated, is that at light loads it is possible to secure flooded 105 operation without use of the circulating pump, and it is possible to cut the circulating pump into action at any time that forced circulation becomes desirable. In both forms of the device circulatory flow is in such direction as to be favorable to the rapid disengagement and discharge of vaporized refrigerant from the evaporator. This follows from the fact that the liquid 110 current follows the path which the gas would follow if there were no forced circulation. The effect is greatly to increase the 115 rate of heat transfer and to insure steady operation of the evaporator at all times by eliminating the possibility of its becoming gas bound.

Various other modifications of the invention 120 will suggest themselves to those skilled in the art, and are contemplated by me, the examples herein illustrated being designed as typical examples showing the commercial applicability of the invention.

I claim:

1. In a brine cooler, the combination of 125 a confining duct; an evaporator in said duct; means for circulating brine through said duct at a velocity of the order of 160 feet 130

- per minute; and power driven circulatory means for circulating volatile liquid refrigerant through said evaporator in quantity greater than evaporable in said evaporator 5 in a single passage of the liquid therethrough.
2. In a brine cooler, the combination of a confining duct; an evaporator in said duct having refrigerant confining passages extending in the direction of the length of the duct; means for circulating brine through said duct at a velocity of the order of 160 feet per minute; and power driven means for circulating volatile refrigerant through 10 said evaporator, in counterflow relation to the brine and in quantity greater than is evaporable in said evaporator during a single passage of the liquid therethrough.
3. In a brine cooler, the combination of 20 a confining duct; an evaporator in said duct including a lower header; an upper header and a plurality of tubes extending from the lower to the upper header, longitudinally through said duct with a rising gradient at all points; power driven means for circulating volatile liquid refrigerant through said evaporator in a direction from the lower header to the upper header in quantity in excess of that evaporable in a single passage 25 through the evaporator; power driven means for circulating brine through the duct in heat exchanging counter current relation with the refrigerant flowing through the evaporator; means for withdrawing vaporized refrigerant from the upper header; and means for supplying liquid refrigerant to the evaporator.
4. In a brine cooler, the combination of a confining duct; power means for circulating brine through said duct; an evaporator in 40 said duct having refrigerant confining passages extending in the direction of the length of the duct and having a rising gradient toward the brine inlet end of the duct; an offtake connection leading from the evaporator adjacent said brine inlet end of the duct; a suction trap connected to said offtake and located above said evaporator; a suction connection leading from said trap; a connection from the bottom of said trap to the end of 45 said evaporator adjacent the discharge end of said duct; a circulating pump interposed in the last named connection and operable to draw volatile liquid refrigerant from said trap and discharge it to said evaporator; a valve controlled by-pass around said pump; and means for supplying refrigerant to the evaporator.
5. In a brine cooler, the combination of a confining duct; power means for circulating brine through said duct; an evaporator in 50 said duct having refrigerant confining passages extending in the direction of the length of the duct and having a rising gradient toward the brine inlet end of the duct; an offtake connection leading from the evaporator adjacent said brine inlet end of the duct; a suction trap connected to said offtake and located above said evaporator; a suction connection leading from said trap; a connection from the bottom of said trap to the end of 55 said evaporator adjacent the discharge end of said duct; a circulating pump interposed in the last named connection and operable to draw volatile liquid refrigerant from said trap and discharge it to said evaporator; and means for supplying refrigerant to the evaporator.
6. In a refrigerating system, the combination of a receiver and an evaporator connected to establish a closed circuit; power circulating means for circulating liquid refrigerant in said circuit; a valve controlled by-pass connecting the inlet and discharge of 60 said power circulating means; a connection for withdrawing vaporized refrigerant from said evaporator; and a connection for supplying liquid refrigerant to said circuit.
7. In a refrigerating system, the combination of a receiver and an evaporator connected to establish a closed circuit leading from the lower portion of the receiver to the bottom of the evaporator, thence upward through the evaporator and from the top of the evaporator to the receiver; power-driven 65 circulating means for positively circulating volatile refrigerant in said closed circuit; a valve controlled by-pass connecting the inlet and discharge of said power circulating means; a suction connection for withdrawing vaporized refrigerant through the top of the evaporator; and a connection for supplying liquid refrigerant to the circuit to 70 compensate for that evaporated.
- In testimony whereof I have signed my name to this specification.

THOMAS SHIPLEY
